[57] **CLAIM**

A new original design for a light-up ball, as shown and described.

DESCRIPTION

FIG. 1 is a perspective view of a light-up ball showing my design;

FIG. 2 is a front elevational view thereof;

FIG. 3 is a rear elevational view thereof;

FIG. 4 is a right elevational view thereof;

FIG. 5 is a left elevational view thereof;

FIG. 6 is a top view thereof; and,

FIG. 7 is a bottom view.

The broken lines shown in FIGS. 1-7 are for illustrative purposes only and form no part of the claimed design.
